UNITED STATES PATENT OFFICE.

EDWIN N. GACKENBACH, OF ORELAND, PENNSYLVANIA.

DESIGN FOR A FLOOR LAMP.

Application filed August 8, 1924. Serial No. 10,417. Term of patent 3½ years.

To all whom it may concern:

Be it known that I, EDWIN N. GACKENBACH, a citizen of the United States, residing at Oreland, in the county of Montgomery and State of Pennsylvania, have invented a new, original, and ornamental Design for a Floor Lamp, of which the following is a specification, reference being

had to the accompanying drawing, forming part thereof.

The figure is an elevational view of a floor lamp showing my new design.

I claim:

The ornamental design for a floor lamp as shown.

EDWIN N. GACKENBACH.
